(57) **CLAIM**

The ornamental design for golf swing training head lock, as shown and described.

DESCRIPTION

FIG. 1 is a front perspective view of golf swing training head lock, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the golf swing training head lock in use;

FIG. 10 is another perspective view showing the golf swing training head lock in use; and,

FIG. 11 is an enlarged detail view of area 11 in FIG. 3.

The broken lines in the drawings illustrate the portions of the golf swing training head lock, which form no part of the claimed design.

The long dash-short dash broken lines in FIGS. 3 and 11 show the boundaries of the enlargements shown in FIG. 11, and form no part of the claimed design.

The broken line showing of a bracket in FIG. 9 and a triangle bracket in FIG. 10 depicts environmental subject matter and forms no part of the claimed design.

1 Claim, 11 Drawing Sheets
